UNITED STATES PATENT OFFICE.

JAMES R. CARDWELL, OF CHICAGO, ILLINOIS, ASSIGNOR TO UNION DRAFT GEAR COMPANY, OF CHICAGO, ILLINOIS, A CORPORATION OF ILLINOIS.

DRAFT-GEAR.

1,069,526.

Specification of Letters Patent.

Patented Aug. 5, 1913.

Application filed August 21, 1909. Serial No. 513,962.

To all whom it may concern:

Be it known that I, JAMES R. CARDWELL, a citizen of the United States, and resident of Chicago, county of Cook, and State of Illinois, have invented certain new and useful Improvements in Draft-Gear, of which the following is a specification, and which are illustrated in the accompanying drawings, forming a part thereof.

10 My invention relates to friction draft gear employed in railway service, and has for one of its objects the provision of means whereby frictional elements are brought into action successively, the lighter stresses 15 incident to either buffing or pulling being resisted by springs, supplemented by a minimum amount of friction—additional frictional elements being available to augment the cushioning action when the stresses are 20 more severe.

A further object of the invention is the provision of means for retaining in place certain laterally movable frictional elements.

25 One embodiment of my invention is hereinafter described, and is illustrated in the accompanying drawing, which shows a detail plan of the center sills and an end sill of a car, and of the improved draft rigging, 30 some of the parts being broken away and some of the parts being shown in section.

A pair of center sills is shown at *a*, *a*, and a portion of an end sill of a car is represented at *b*.

35 The coupler is shown at *o*, and the usual yoke secured to the butt of the coupler bar and inclosing the shock-resisting elements is designated *n*. The forward draft lugs are shown at *c*, *c*, and the rearward draft lugs 40 at *d*, *d*. The forward follower *g* co-operates with the lugs *c*, *e*, and a rearward follower *h* with the lugs *d*, *d*. Each of these followers is shown as of the box type, being provided with inwardly projecting top and 45 bottom and side flanges which form chambers *g*², *h*², within which the friction elements are housed.

A bolt *r* projects horizontally through the sills *a*, *a*, and yoke, elongated slots *y*, *y*, 50 being formed in the sills for its accommodation. Helical springs *s*, *s*, are mounted one upon each end of the bolt *r* outside of the sills, and react between outer abutments *u*, *u*, adjustably fixed upon the ends of the 55 bolt and abutments *t*, *t*, sleeved upon the

bolt, their stems projecting inwardly through the apertures in the sills.

A pair of blocks *q*, *q*, is sleeved upon the bolt *r*, the outer faces of these blocks bearing, respectively, against the inner ends of the stems of the abutments *t*, *t*, and their inner faces being beveled or inclined outwardly toward each end. A second pair of blocks *q*², *q*², is sleeved upon the bolt *r* between the blocks *q*, *q*, the inner faces of these blocks being preferably in contact or in close proximity when the gear is in its normal position, these inner faces being preferably flat and perpendicular to the axis of the bolt except adjacent their ends, 70 which are beveled outwardly. The inner portions of the outer faces of the blocks *q*², *q*², are preferably recessed to receive the inner faces of the blocks *q*, *q*, and at their ends are beveled inwardly, thereby normally providing V-shaped recesses with the outer ends of the inclined faces of the blocks *q*, *q*.

The followers *g*, *h*, are provided, respectively, with instanding ribs *g*³, *h*³, on their vertical median lines, these ribs being V-shaped in cross-section and entering between the blocks *q*², *q*². Wedge-blocks *g*', *g*', and *h*', *h*', each having preferably the form of an equilateral triangle in plan section, are located, respectively, adjacent the inner faces of the followers *g*, *h*, one upon each of said instanding ribs thereof *g*³, *h*³, and enter the V-shaped openings between the end portions of the blocks *q*, *q*², the sizes 90 of the blocks *g*', *h*', and of the recesses between the blocks *q*, *q*², being such that lost motion is provided; that is to say, the blocks *g*', *h*', when in contact with the inner faces of the followers, with which they 95 have lateral sliding engagement, are out of contact with the blocks *q*, *q*², when the gear is in its normal position.

Under the influence of either buffing or pulling stresses there is a relative approach 1. of the followers, which cause the advance of the ribs *g*³, *h*³, between the blocks *q*², *q*², forcing the latter apart against the resistance of the springs *s*, *s*, thus developing frictional resistance between the ribs *g*³, *h*³, 105 and the blocks *q*², *q*², the bolt *r*, and the parts sleeved upon it, being moved laterally.

As the followers continue to approach, the wedge-blocks *g*', *h*', come into engagement 110 with the inclined faces of the blocks *q* and

q^2 , and slide thereupon, developing friction and forcing the blocks q , q , outwardly, the blocks g' , h' , being also moved outwardly, bearing frictionally upon the inner faces of 5 the followers.

The initial friction, developed only between the ribs g^3 , h^3 , and the blocks q^2 , q^2 , is comparatively slight. The friction developed under heavy stresses is greatly augmented, as it is developed by all three of 10 the faces of the blocks g' , g' , h' , h' , with other elements of the gear.

While the blocks g' , h' , are loose when the gear is in its normal position, they are, 15 nevertheless, prevented from displacement by the contiguity of the various elements of the gear with which they coöperate when brought into action. All of the parts are restored to their normal positions upon the relief of the stresses of service by the action of the springs s , s . While the ribs g^3 , h^3 , are shown as and are preferably integral parts of the followers, this is not essential 20 to the action of the device.

25 The invention is shown in connection with a draft gear of the type disclosed in my Patent No. 819,266, dated May 1st, 1906, but I do not limit myself to this form of draft gear, the invention in its broader aspects being applicable to other types.

I claim as my invention—

35 1. In a draft gear, in combination, a pair of opposed followers, normally engaged friction elements coöperating with the followers and supplemental elements frictionally coöperating with the first named friction elements after the initial advance of either follower and being normally out of frictional engagement with the first named 40 friction elements.

45 2. In a draft gear, in combination, a pair of opposed followers, a pair of spring-advanced laterally movable friction blocks, wedging friction elements associated with the followers and entering between and normally engaged with the blocks, additional friction elements associated with the fol-

lowers and engageable but normally out of engagement with the blocks and means for resisting the outward lateral movement of 50 the additional frictional elements.

3. In a draft gear, in combination, a pair of opposed followers, a pair of laterally movable juxtaposed blocks located between the followers and having their inner and outer faces beveled at their ends, springs urging the blocks together, a wedge projecting inwardly from each follower and engaging the inner faces of the blocks, laterally movable wedge-blocks engageable with 60 the inner face of each follower and located on opposite sides of the first-named wedges and coming into engagement with the outer faces of the juxtaposed blocks as the followers advance toward each other and means 65 for resisting the outward movement of the lateraliy movable wedge-blocks.

4. In a draft gear, in combination, a pair of opposed followers, a pair of laterally movable juxtaposed blocks located between 70 the followers and having their inner and outer faces beveled at their ends, a second pair of blocks bearing against the outer faces of the first-named blocks and having the ends of their inner faces beveled, springs 75 urging the blocks together, a wedge projecting inwardly from each follower and engaging the inner faces of the first-named blocks, and laterally movable wedge-blocks engageable with the inner face of each follower 80 and located on opposite sides of the first-named wedges and coming into engagement with the outer faces of the juxtaposed blocks and with the inner faces of the second-named blocks as the followers advance 85 toward each other.

In witness whereof, I hereunto subscribe my name this 20th day of August, A. D. 1909.

JAMES R. CARDWELL.
